MOTION PICTURE CAMERA

Frederick G. Knowles, Rochester, N.Y., assignor to Eastman Kodak Company, Rochester, N.Y., a corporation of New Jersey

Application July 3, 1959, Serial No. 56,649

Term of patent 14 years

(Cl. D61—1)

Fig. 1

Fig. 2

Fig. 3

Fig. 1 is a front perspective view of a motion picture camera showing my new design;

Fig. 2 is a rear perspective view thereof; and

Fig. 3 is a partial sectional detail taken substantially on line 3—3 of Fig. 1.

The dominant features of my new design are shown in solid lines in the drawing. Since the bottom of the camera has substantially the same appearance as the top it has not been shown.

I claim:

The ornamental design for a motion picture camera, as shown and described.
